UNITED STATES PATENT OFFICE.

WILLIAM PEET, OF KANSAS CITY, MISSOURI.

BOX-SEALING MACHINE.

1,390,059.

Specification of Letters Patent. Patented Sept. 6, 1921.

Application filed May 21, 1919. Serial No. 298,708.

To all whom it may concern:

Be it known that I, WILLIAM PEET, a citizen of the United States, and a resident of Kansas City, county of Jackson, State of Missouri, have invented a certain new and useful Box-Sealing Machine, of which the following is a specification.

The invention relates to machines for holding the sealing flaps of boxes in place during the sealing operation.

An object of the invention is to provide a machine for firmly and securely holding the sealing flaps of a box in place during the time that the adhesive is setting.

Another object of the invention is to provide a box sealing machine which may be adjusted for sealing boxes of different heights.

A further object of the invention is to provide means for feeding the boxes to which the adhesive has been applied, to the pressing and holding means and to provide box operated means for throwing the feeding mechanism into operation and further means for stopping the feeding mechanism after the box has been placed in the pressing and holding means.

The invention possesses other advantageous features, some of which, with the foregoing, will be set forth at length in the following description, where I shall outline in full, that form of the invention which I have selected for illustration in the drawings accompanying and forming part of the present specification. In said drawings I have shown one specific form of my invention, but it is to be understood that I do not limit myself to such form, since the invention, as expressed in the claims, may be embodied in a plurality of forms.

Referring to said drawings:

Figure 1 is a side elevation of the front end of the machine, showing the feeding mechanism, the feeding mechanism controlling means and the forward end of the pressing and holding means.

Fig. 1^a is a side elevation of the rear end of the machine.

Fig. 2 is a plan or top view of that portion of the machine shown in Fig. 1.

Fig. 2^a is a plan view of the continuation of the pressing and holding means.

Fig. 3 is a cross section through the pressing and holding means, taken on the line 56 3-3, Fig. 1.

Fig. 4 is a plan view of the feed control means.

The machine of my invention is particularly adapted for use in sealing fiber, cardboard, straw-board, corrugated board and other boxes having sealing end flaps and side flaps which are folded into position and adhesively secured in position. The end flaps are usually first folded into position on the filled box and the upper surfaces thereof coated with glue or other adhesive and then the side flaps are folded into position in contact with the glued surfaces of the end flaps and then held firmly and pressed tightly against the folded end flaps until the glue sets.

The machine of my invention comprises a conveyer comprising a plurality of parallel free rollers 3 over which the filled and unsealed boxes travel from the packing station 75 to the sealing machine. From the conveyer the boxes 4 are moved to the feeding apparatus which is disposed adjacent the end of the conveyer. The feeding apparatus comprises a table composed of a plurality of 80 parallel free rollers 5, on which the unsealed boxes are set. The end flaps 6 of the box are then folded down and the upper surfaces thereof coated with glue or other adhesive and then the side flaps 7 are folded down 85 into engagement with the glued surfaces. The box is then ready to be fed into the pressing and holding mechanism. In the present instance the side flaps 7 are of slightly less width than one-half the box, so 90 that when folded, the adjacent ends of the side flaps are slightly spaced apart.

The feed table rollers 5 are journaled in a suitable frame 8, and secured to the opposite ends of the shafts of the front and rear 95 rollers 5, respectively, are sprockets 12 and 13, preferably disposed on the outside of the frame. Engaging each pair of sprockets 12-13 is an endless drive chain 14, there being one chain 14 on each side of the frame. The chains are driven by the sprockets 15, secured to the shaft 16 journaled below the rollers 5, which shaft is driven by the chain 17 engaging the sprocket 18 on the shaft 16. The chain 17 is driven by the sprocket 19 100 secured to the shaft 21, which latter shaft is driven through the clutch 22 by the belt 23 connected to the motor 24 or other source of power. The upper run of the chains 14 moves in a plane above the upper surfaces 110

- of the rollers 5 and these chains are connected by pushers, preferably in the form of one or more rollers 25 which extend transversely across the feed table. The rollers 25 are mounted at their opposite ends in brackets 26 secured to the chains and to prevent the chains from being unduly kinked while the pushing roller is advancing a filled box, the brackets 26 are provided with backward extensions 27 which bear against the chains at a distance behind the pushers, thereby causing the axis of the pusher roller to pivot, as it were, at a point behind the roller and thereby prevent any undue kinking or distortion of the chain due to the load being pushed. In the machine shown in the drawings, I have shown two pusher rollers, but I do not limit myself to the use of such number of pusher rollers.
20. The flap pressing and box holding mechanism is arranged at the discharge end of the feed table and the pusher rollers move the boxes directly into the pressing and holding mechanism. The operation of the feeding chains 14 is intermittent and box operated means are provided for throwing the chains into operation, to cause the pusher to move the box from the feed table. Journaled at one side of the feed table frame, is a vertical shaft 28, to which is fixed an arm 29 which projects over the feed table into the path of a box moving thereover. Secured to the shaft 28 is a lever 31 which is mediate connected to the clutch shipper head 32 by the link 33 and lever 34. The movement of the shipper head 32 caused by the deflection of the arm 29 by the box, throws the clutch in engagement, causing the chains 14 to be driven to push the box into the pressing mechanism. The operator after he has applied the glue and folded the flaps, pushes the box against the arm 29, throwing the feed mechanism into operation.
45. After the box has been discharged from the feed table, the pusher roller moves into contact with a lever 35 arranged adjacent the discharge end of the table and in the path of the pusher roller. The lever 35 is pivoted to the frame of the pressing mechanism and is connected by a link 36 with a bell crank 37 which in turn is connected to the bell crank 38 by the link 39. The bell crank 38 is connected to the lever 34 by the link 41 and the lever 34 is connected to the clutch shipper head 32 as heretofore set forth. The movement of the lever 35 by the pusher roller moves the shipper head in a direction to disengage the clutch, thereby halting the movement of the feeding chains.
- From the feed table, the box is fed into the pressing and holding mechanism. This mechanism comprises a frame having two sets of freely rotatable rollers 42-43 journaled thereon, the rollers being horizontally disposed and parallel and the two sets being spaced apart vertically, so that the box passes between the upper and lower rollers. The lower rollers 42 are journaled on shafts 44 secured to the angle irons 45 arranged at opposite sides of the frame. The upper rollers 43 are journaled on shafts 46 which are attached to the plungers 47 bearing in the channels 48 and pressed downwardly by the springs 49, so that the upper rollers are yieldingly mounted and press against the folded side flaps 7. The upper rollers 43 are provided at their centers with circumferential grooves 51 which overlie the gap between the two side flaps, so that any glue which may be expressed at this point does not contact with the rollers. The upper set of rollers is adjustable, as a whole, vertically, so that the machine may be adjusted for handling boxes of various depths. Secured to the angle iron 45, which are disposed on opposite sides of the pressing apparatus, are plates 52, through which are threaded a plurality of threaded spindles 53 at spaced points. The spindles are rotatably supported adjacent their upper ends on brackets 54 secured to the channels and are provided at their upper ends with hand wheels 55, whereby the spindles may be rotated. Rotation of the spindles causes the plunger carrying channels to be raised or lowered, thereby varying the vertical distance between the upper and lower sets of rollers. Vertical guide rods 56, secured to the frame at intervals and engaging in bearings 57 on the angle iron, guide the channels in their vertical movement and hold the channels in proper position transversely with respect to the frame.
- Means are also provided for preventing any flattening or distortion of the box due to the sealing pressure of the rollers, and to prevent any slip of the side flaps over the end flaps before the glue has set. Arranged at the forward end of the pressing apparatus and on each side thereof, are a plurality of spaced rollers 58, which engage the sides of the box adjacent the top, to hold the sides firm against the sealing pressure. The rollers 58 are arranged relatively close together and are journaled in frames 59 arranged on opposite sides of the box runway. The frames 59 are supported on a plurality of adjusting screws 61 threaded through the brackets 62 secured to the channels. By moving the screws 61, the spacing between the rollers 58 on opposite sides of the box runway may be readily adjusted for boxes of different widths. The frames 59 are connected to the channels 48, so that their vertical position with respect to the upper rolls remains fixed.
- At the forward end of the machine, the rollers 42 and 43 in each set are arranged close together, so that a relatively uniform

- pressure is exerted on the boxes to effect a perfect distribution and penetration of the glue and to prevent any movement of the flaps, but toward the discharge end of the machine, the rollers in the two sets are spaced apart farther, since greater spacing is permissible when the glue has started to set.
- The boxes are not only fed into the pressing rollers by the feeding mechanism, but are also advanced through the feeding rollers by the feeding mechanism, the entering box serving to push the others ahead of it.
- 15 I claim:
1. An apparatus for sealing boxes, comprising pressing means through which the boxes pass, mechanism for feeding boxes into the pressing means, and means operated by the box for throwing the feeding mechanism into operation.
  2. An apparatus for sealing boxes, comprising pressing means, a feed table arranged in front of the pressing means, mechanism for moving boxes over the feed table and into the pressing means, and means adapted to be engaged by a box on the feed table for throwing the moving mechanism into operation.
  3. An apparatus for sealing boxes, comprising box pressing means, a feed table arranged in front of the pressing means, a pusher arranged to move over the feed table to push the box into the pressing means, mechanism for moving the pusher and mechanism control means arranged over the feed table in the path of the box.
  4. An apparatus for sealing boxes, comprising box pressing means, a feed table arranged in front of the pressing means, a pusher movable over the feed table to push the box into the pressing means, mechanism for moving the pusher and control means adapted to be engaged by the pusher for throwing the pusher moving mechanism out of operation.
  5. In an apparatus for sealing boxes, a feed table, a pusher movable over the feed table, pusher moving mechanism, means disposed over the table for throwing the mechanism into operation, and means arranged to be engaged by the pusher for throwing the mechanism out of operation.
  6. In an apparatus for sealing boxes, a plurality of parallel rollers forming a feed table, a pusher arranged to move over the table to discharge the box therefrom, power driven means for moving the pusher, and means operated by the manual movement of a box over the table for throwing the power driven means into operation.
  7. In an apparatus of the character described, a feed table, a pusher arranged to move over the table to discharge the box therefrom, power driven means for moving
- the pusher, and means operated by the manual movement of a box over the table for throwing the power driven means into operation.
8. In an apparatus of the character described, a feed table, a pusher arranged to move over the table to discharge the box therefrom, power driven means for moving the pusher, means operated by the manual movement of a box over the table for throwing the power driven means into operation and a device adapted to be engaged by the pusher after the box has been discharged, for throwing the power driven means out of operation.
9. In an apparatus of the character described, a plurality of parallel rollers comprising a feed table, endless chains arranged at opposite sides of the table, a pusher secured to said chains and adapted to move over the table to discharge a box therefrom, a driving sprocket engaging said chains, a shaft adapted to be continuously driven from a source of power, a clutch between said shaft and sprockets, means operative by a manual movement of a box over the table for engaging said clutch, and means operated by contact with the pusher after the box is discharged, for disengaging said clutch.
10. In an apparatus of the character described, box feeding mechanism, means for throwing the feeding mechanism into operation, and means operated by said feeding mechanism for throwing the feeding mechanism out of operation.
11. An apparatus for sealing boxes, comprising a frame, a set of horizontally disposed parallel rollers mounted on said frame, a second frame arranged above said first frame, means for raising and lowering said second frame, vertically disposed spring pressed plungers mounted in said second frame, a set of horizontally disposed parallel rollers mounted in said plungers and spaced from said first set forming therebetween a box passageway, and vertically disposed parallel rollers carried by said second frame and arranged on both sides of said passageway, adapted to engage the upper portion of the box sides and to maintain a substantially fixed relation vertically with respect to the upper set of said horizontal rollers.
12. An apparatus for sealing boxes, comprising a box passageway including a set of yieldingly mounted parallel rollers adapted to press against one of the box ends during the passage of the box therethrough, and means adjustable in a plane parallel to the sides of the box adapted to engage the box side adjacent the end that is being sealed.
13. An apparatus for sealing boxes, comprising a frame, a set of horizontally dis-

- posed parallel rollers mounted on said frame, a second frame arranged above said first frame, a set of horizontally disposed parallel rollers yieldingly mounted on said 5 second frame and forming with said first set of rollers a box passageway, means for raising and lowering said second frame, and means supported at the sides of said passageway adjustable in a plane parallel to the 10 sides of the boxes and adapted to engage the upper portion of the box sides.
14. An apparatus for sealing boxes, comprising a frame, a set of horizontally disposed parallel rollers mounted on said 15 frame, a second frame arranged above said first frame, means for raising and lowering said second frame, vertically disposed spring pressed plungers mounted in said second frame, a set of horizontally disposed 20 parallel rollers mounted in said plungers and spaced from said first set forming therebe-
- tween a box passageway, and means arranged on both sides of said passageway, supported on one of said frames and adjustable in a plane parallel to the sides of 25 the boxes adapted to engage the upper portion of the box sides.
15. An apparatus for sealing boxes, comprising a box passageway, including means adapted to press against one of the box ends 30 during the passage of the box therethrough, and means adjustable in a plane parallel to the sides of the box adapted to engage the box side adjacent the said end.

In testimony whereof I have hereunto set 35 my hand at Oakland, California, this 26th day of April, 1919.

WILLIAM PEET.
